CLAIM

The ornamental design for an ear pick, as shown and described.

DESCRIPTION

FIG. 1 is a perspective view of an ear pick showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the ear pick where the ear pick is in a use state; and,

FIG. 10 is an enlarged view of portion 10 shown in FIG. 1. The even length broken lines immediately adjacent to the shaded areas depict the bounds of the claimed design, while all other even length broken lines are directed to environment. In addition, the dot-dash broken lines illustrate enlarged portions of the design. None of the broken lines forms part of the claimed design.
